Ed S. Billman, attorney

UNITED STATES PATENT OFFICE.

DAVID LAMBERT, OF CLEVELAND, OHIO.

KNIFE SHARPENER

Application filed November 15, 1923. Serial No. 570,805

To all whom it may concern:

Be it known that I, DAVID LAMBERT, a citizen of the United States, residing at Cleveland, in the county of Cuyahoga and State of Ohio, have invented certain new and useful Improvements in Knife Sharpeners, of which the following is a specification.

My invention relates to improvements in knife sharpeners, the present embodiment of the invention being particularly designed and adapted for use in quickly sharpening kitchen or household knives of various forms and types.

The primary object is to provide a generally improved knife sharpener, which will be exceedingly simple in construction, cheap of manufacture and efficient in use.

A further and very important object is the provision of an improved form and arrangement of sharpening discs extending toward each other in overlapping relation and conjointly forming a V-shaped article receiving and sharpening recess, said cutting or sharpening discs being arranged in gangs and loosely mounted on gang axle shafts so that the same are adapted to be tilted or canted on such axle shafts to present one edge or the other of the sharpening discs against the article edge to be sharpened in accordance with the direction in which the article edge is drawn.

A further and important object is the provision of loosely mounted and spaced cutting and spacing discs adapted to move or creep around the axle shaft circumferentially as being operated upon by the article being sharpened, thereby presenting variable cutting edges, the knife edge sharpening or cutting discs being of suitable tempered steel and ground to a perfect cutting edge and being adapted to be removed for re-grinding when dull.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1 is a side elevation of a knife sharpener constructed in accordance with this invention.

Fig. 2, a cross sectional view of the same, taken on line 2--2 of Fig. 1.

Fig. 3, an enlarged top plan view of a pair of overlapping sharpening discs in canted or tipped relation to the supporting axles in their active article sharpening relation. 60

Fig. 4, an enlarged fragmentary view of the tilted or canted sharpening discs presenting their edges in active sharpening relation to the edge of the article being sharpened in accordance with the direction in which the latter is drawn or reciprocated.

Fig. 5, an end elevation of a set of loosely mounted sharpening discs and a supporting axle, detached from the supporting frame or holder therefor.

Similar numerals of reference designate like parts throughout all the figures of the drawings.

The improved sharpener comprises a suitable support or holder carrying a pair of 75 gangs of loosely mounted overlapping cutting or sharpening discs forming an article receiving and sharpening recess and loosely mounted on suitable axle members so that the same may be tilted or canted to present 80 their edges at acute angles to the edge of the article to be sharpened as the latter is drawn over said cutting edges of the discs, as hereinafter fully referred to.

The support or holder may be of any suitable and convenient construction, said support, in the present instance, comprising a suitable base 1^a, adapted when in use to rest upon a suitable support, such as a table, shelf, or the like, said support or holder including spaced bearing members or brackets 1, adapted to receive and carry suitable bearing members or axle shafts 1^b. The axle members 1^b may be fixed or secured in the bearing members 1 in any suitable and convenient manner, as for example,—by means of rivet heads 1^c and smaller upset heads 1^d. In the present instance, the brackets 1 and base 1^a are connected by end walls 1^e, thereby forming a receptacle for the sharpening and spacing discs, mounted and arranged as hereinafter referred to, and adapted to receive and carry the cuttings and other foreign substances arising from the sharpening operation. In the present instance, the receptacle forming base or support is provided with a handle, 1^f, but it will be understood that the support may be permanently secured upon a table or shelf in any suitable or well known manner. 100 105 110

As a means of enabling the cutting or sharpening discs 2, to be tilted or canted

in their active knife sharpening operation, as well as leaving such discs free to creep around the shafts 1^b to thereby present variable cutting edges, the sharpening discs 2 are provided with openings 2^a, somewhat larger than the bearing shafts 1^b, as shown most clearly in Fig. 5 of the drawings, and as a means of holding the sharpening discs 2 in proper spaced relation to each other, suitable spacing discs 3, are provided, said gangs of discs 2 and 3 being of an aggregate thickness or cross dimension of considerable less than the dimension of the space between the bearing brackets 1, as shown most clearly in Fig. 2 of the drawings. The spacing discs 3 are likewise provided with bearing openings of larger diameter than the axle members 1^b and it will be seen that the sharpening discs 2 extend toward each other in overlapping relation and conjointly form a V-shaped article receiving and sharpening recess 4, a somewhat similarly shaped but larger recess 1^c being provided in the support between the bracket members 1, as shown.

The outer peripheries of the sharpening discs 2 are preferably ground so as to present relatively sharp cutting edges 2^b against the cutting edge of the article 5 to be sharpened when the latter is drawn over such cutting edges, as shown most clearly in Figs. 3 and 4 of the drawings. For example,—when the article 5 is drawn in the direction of the arrows the sharpening discs will be tilted or canted as there shown, thereby presenting the outer peripheries or cutting edges 2^b at an acute angle to the cutting edge of the article being sharpened, and it will be understood that if the knife or article being sharpened is reciprocated or drawn in a reverse direction to that shown in Figs. 3 and 4 of the drawings, the cutting discs 2 will be tilted or canted in a reverse direction, bringing the opposite cutting edges 2^b into action.

Having thus described one of the embodiments of my invention, without having attempted to set forth all the forms in which it may be made, or all the modes of its use, what I claim and desire to secure by Letters

Patent is,—

1. In a knife sharpener, a support, and gangs of spacing and overlapping sharpening discs loosely mounted and cantable on said support with their edges at acute angles to the surface of the article being treated.

2. In a knife sharpener, a plurality of loosely mounted spacing and sharpening discs the latter being arranged in overlapping wobbling relation transversely of their axes to present acute article sharpening edges.

3. In a knife sharpener, a support carrying gangs of loosely mounted spacing and overlapping sharpening discs laterally oscillatory on their axes thereby presenting their

edges at acute angles to the edge of the article being sharpened when moved to one extreme position or the other by the movement of the latter.

4. In a knife sharpener, a plurality of spacing discs and a plurality of overlapping sharpening discs between said spacing discs having their peripheries ground at right angles to their longitudinal planes and means for axially supporting and permitting said discs to be rocked thereby presenting said peripheries at acute angles to an article being sharpened.

5. In a knife sharpener, gangs of loosely mounted overlapping sharpening discs including disc spacing elements forming an article receiving recess and loosely mounted and tiltable with their edges at acute angles to the plane of movement of the article being sharpened.

6. In a knife sharpener, spacing discs, and overlapping sharpening discs having their peripheries ground at right angles to their longitudinal planes and means for supporting said discs in gangs and permitting the same to be canted by the article being sharpened bringing said peripheries at acute angles to the plane of movement of said article.

7. In a knife sharpener, a support including axle shafts carrying gangs of loosely mounted spacing and overlapping sharpening discs forming an article receiving recess said discs being provided with bearing openings larger than said axle shafts permitting said discs to have a limited rocking motion thereby presenting their edges at acute angles to the edge of the article to be sharpened as the latter is drawn over said edges.

8. In a knife sharpener, a support including axle shafts carrying gangs of overlapping sharpening discs conjointly forming an article sharpening recess said sharpening discs having enlarged bearing openings on said axle shafts permitting said discs to oscillate axially on said axle shafts and presenting their edges at acute angles to the edge of the article being sharpened and in accordance with the direction in which the latter is drawn, and spacing discs having enlarged bearing openings on said axle shafts and loosely interposed between said sharpening discs.

9. In a knife sharpener, a support including spaced bearing brackets carrying axles extending therebetween, and gangs of spacing and sharpening discs loosely mounted on said axle, said sharpening discs overlapping each other and being provided with bearing openings larger in diameter than said axles whereby said sharpening discs are canted by the article being sharpened so as to cause their planes to intersect thereby presenting their edges at acute cutting angles thereto.

10. In a knife sharpener, a support in-

- cluding axle shafts extending transversely thereof, gangs of sharpening discs loosely mounted thereon and extending toward each other in overlapping relation and conjointly forming an article receiving and sharpening recess, and spacing discs being loosely mounted on said axle shafts between said sharpening discs, provided with bearing openings larger in diameter than said axle shafts permitting said sharpening discs to be canted in one direction or the other as the article is drawn thereover thereby presenting the edges thereof at acute angles to the edge of the article being sharpened.
11. A knife sharpener, comprising a support including spaced bearing members, axle shafts carried by the latter, and sharpening and spacing discs loosely mounted on said axle shafts, said sharpening discs extending toward each other in overlapping relation and conjointly forming a V-shaped article receiving and sharpening recess, said sharpening discs being provided with bearing openings larger than said axle shafts whereby said discs may be canted on said axle shafts to present one edge or the other of said sharpening discs against the article edge to be sharpened in accordance with the direction in which the article is drawn.
12. A sharpener comprising a support, and axially arranged sharpening disks tiltably mounted on said support.

In testimony whereof I have affixed my signature.

DAVID LAMBERT.
